UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

SIGNALING SYSTEM.

Application filed August 19, 1921, Serial No. 493,670, and in France November 17, 1917.

(GRANTED UNDER THE PROVISIONS OF THE ACT OF MARCH 3, 1921, 41 STAT. L., 1313.)

This invention comprises an improvement in or modification of the invention claimed in my prior Patent No. 1,584,701, granted May 11, 1926, in which is described in an 5 amplifier with thermionic tubes or audions wherein amplification is conducted in stages the use of a common source for supplying with current the plate-filament circuits of the audions of the various stages.

10 In my mentioned patent an amplifying system was described in which the same audions serve for an amplification of the high-frequency currents and of the low-frequency currents.

15 The present invention provides apparatus wherein, as in the preceding application referred to, the same audions serve for amplification of the high frequency currents and of the low frequency currents and 20 in which two high frequency transformers are provided for enabling two supplementary stages of amplification to be effected at high frequency and two low frequency transformers enable two stages of amplification at low frequency to be effected.

25 In the accompanying drawing illustrating this invention:

The thermionic tubes or audions 1, 2, 3, 4 have their filaments heated by the battery 30 5 and their plates supplied with current by the battery 6.

The high-frequency current to be amplified, viz, the wireless telegraphy or telephony reception, is led to the terminals 7 35 and 8 a capacity 9 being interposed on the filament side. This capacity 9 enables the positive pole of the battery 6 to be earthed at 28 without inconvenience even when no telephone transformer is used. The high-frequency transformers 10, 11 enable two supplementary stages of amplification to be carried out at high frequency and the high-frequency transformer 12 serves to supply current to the detector lamp 4 through the 40 shunted capacity 22. The low-frequency transformers 13 and 14 enable two stages of amplification at low frequency to be carried out with the lamps 2 and 3. Listening takes place between the terminals 15 and 45 16, either directly or with the interposition of a telephonic transformer. The capacities 17, 18, 19, 20 and 21 suitably located, let the high frequency currents pass. In

practice there may be established on the 55 transformers 13 and 14 windings such that the capacities 17, 18, 19 and 20 (more particularly the capacities 17 and 20) may be omitted. A connection has moreover been shown in the drawing between the plates of the audions 3 and 4. This connection is 60 established through the capacity 23. Its object is to increase the amplification if possible. Quite generally, it should be conceived that for the purpose of obtaining this result the connection between the plates 65 of the audions 3 and 4 may be made with a self-inductance 27 in series with a capacity.

Having described my invention, what I claim is:

1. In apparatus for amplifying high frequency electrical oscillations having a low frequency component, a plurality of three element tubes connected in cascade, a detector associated with the output of the 75 last tube of the cascade, means for applying the detected currents to the input circuit of one of said tubes other than the last of the cascade, and a low frequency transformer in a circuit intermediate the input of said other tube and the output circuit of said last tube of the cascade.

2. In apparatus for amplifying high frequency electrical oscillations having a low frequency component, a plurality of 85 three element tubes connected in cascade, a detector associated with the output of the last tube of the cascade and a low frequency transformer coupling the output of the detector to the input of one of said tubes 90 other than the last tube of the cascade.

3. In apparatus for amplifying high frequency electrical oscillations having a low frequency component, a plurality of three element tubes connected in cascade, 95 a detector associated with the output circuit of the last tube of the cascade, means for applying the detected currents to the input of one of said tubes other than the last tube of the cascade, a low frequency 100 transformer in the output circuit of said other tube, and indicating means in the output circuit of a tube succeeding said other tube.

4. In apparatus for amplifying high 105 frequency electrical oscillations having a

low frequency component, a plurality of three element tubes connected in cascade, a detector associated with the output of the last tube of the cascade, means for applying the detected currents to the input of one of said tubes other than the last tube of the cascade, a low frequency transformer in the output circuit of said other tube and indicating means in the output circuit of the tube preceding the detector.

5. In apparatus for amplifying high frequency electrical oscillations having a low frequency component, a plurality of three element tubes connected in cascade, a detector associated with the output of the last tube of the cascade, means for applying the detected currents to the input circuit of one of said tubes other than the last tube of the cascade, means including a low frequency transformer for interlinking the input of said other tube and the output circuit of the last tube of the cascade, and indicating means in the output circuit of one of said tubes.

25. 6. In apparatus for amplifying high frequency electrical oscillations having a low frequency component, a plurality of three element tubes connected in cascade, a detector associated with the output of the last tube of the cascade, means for applying the detected currents to the input circuit of one of said tubes other than the last tube of the cascade, means including a low frequency transformer for interlinking the input of said other tube and the output of the last tube of the cascade, and indicating means in the output circuit of the last tube of the cascade.

7. In apparatus for amplifying high frequency electrical oscillations having a low frequency component, a plurality of three element tubes connected in cascade, a detector associated with the output of the last tube of the cascade, a low frequency transformer coupling the output of said detector with the input of a tube other than the last tube of the cascade, and means including a low frequency transformer for interlinking the input of said other tube and the output of the last tube of the cascade.

40. 8. In apparatus for amplifying high frequency electrical oscillations having a low frequency component, a plurality of three element tubes connected in cascade, a detector associated with the output of the last tube of the cascade, means for applying the detected currents to the input circuit of one of said tubes other than the last tube of the cascade, means including a low frequency transformer for interlinking the input circuit of said other tube and the output circuit of the last tube and capacity associated with said low frequency transformer for by-passing the high frequency currents.

65. 9. In apparatus for amplifying high fre-

quency electrical oscillations having a low frequency component, a plurality of three element tubes connected in cascade, a detector associated with the output circuit of the last tube of the cascade, means for applying the detected currents to the input of one of said tubes other than the last tube of the cascade, and two transformers coupling the output circuit of said other tube with the input circuit of the next succeeding tube, one of said transformers being for low frequency and the other for high frequency currents.

10. In high frequency signalling systems, the combination of a plurality of thermionic amplifying elements, each having its output circuit coupled through a high frequency transformer to the input circuit of another of said elements, and at least one of said elements having its output circuit coupled through an additional and lower frequency transformer to the input circuit of another of said elements, and means for shunting high frequency currents around said lower frequency transformer.

11. In high frequency signalling systems, the combination of a plurality of thermionic amplifying elements, each having its output circuit coupled through a high frequency transformer to the input circuit of another of said elements and at least one of said elements having its output circuit coupled through an additional and lower frequency transformer to the input circuit of another of said elements, and indicating apparatus associated with the output circuit of the last element having such additional lower frequency coupling in the input circuit thereof.

12. In high frequency signalling apparatus, the combination of a plurality of thermionic amplifying elements coupled in cascade, a detector coupled to the last of said elements, and means for coupling the output circuit of said detector to the input circuit of one of said elements, the coupling between said elements except the first two comprising a relatively high frequency transformer and a lower frequency transformer, and the coupling between the last said element and the detector comprising a high frequency transformer only.

13. In a radio receiver, the combination of a plurality of thermionic amplifying elements in cascade, each provided with an input circuit and an output circuit, means for doubly coupling the output circuit of one thermionic amplifying element to the input circuit of another thermionic amplifying element, said coupling means including high frequency and low frequency devices, a detector linked to the last thermionic amplifying element of the cascade, and means for coupling said detector to said first mentioned thermionic amplifying element.

MARIUS LATOUR.
